(57) **CLAIM**

The ornamental design for a spotting scope, as shown and described.

DESCRIPTION

FIG. 1 is a perspective view of a first embodiment of the spotting scope of our new design;

FIG. 2 is a top plan view of the spotting scope of FIG. 1;
FIG. 3 is a bottom plan view of the spotting scope of FIG. 1;

FIG. 4 is a right side elevation view of the spotting scope of FIG. 1;

FIG. 5 is a left side elevation view of the spotting scope of FIG. 1;

FIG. 6 is a front elevation view of the spotting scope of FIG. 1;

FIG. 7 is a rear elevation view of the spotting scope of FIG. 1;

FIG. 8 is a perspective view of a second embodiment of the spotting scope of our new design;

FIG. 9 is a top plan view of the spotting scope of FIG. 8;
FIG. 10 is a bottom plan view of the spotting scope of FIG. 8;

FIG. 11 is a right side elevation view of the spotting scope of FIG. 8;

FIG. 12 is a left side elevation view of the spotting scope of FIG. 8;

FIG. 13 is a front elevation view of the spotting scope of FIG. 8; and,

FIG. 14 is a rear elevation view of the spotting scope of FIG. 8.

The stippling shown in FIGS. 1 to 7 depicts a contrasting appearance and forms part of the claimed design.

The broken lines depict portions of the spotting scope and form no part of the claimed design.

1 Claim, 12 Drawing Sheets
